US00D693749S

(12) **United States Design Patent**
Ewingmann

(10) **Patent No.:** **US D693,749 S**
(45) **Date of Patent:** **** Nov. 19, 2013**

(54) **EXTENSION ARM WITH LIGHT AND MIRROR FOR A ROAD CONSTRUCTION MACHINE**

(75) Inventor: **Ulrich Ewingmann,**
Taufkirchen-Potzharn (DE)

(73) Assignee: **Joseph Vögele AG**, Ludwigshafen/Rhein (DE)

(**) Term: **14 Years**

(21) Appl. No.: **29/412,340**

(22) Filed: **Feb. 1, 2012**

(30) **Foreign Application Priority Data**

Aug. 1, 2011 (DE) 001289920

(51) **LOC (9) Cl.** **12-16**

(52) **U.S. Cl.**

USPC **D12/187**

(58) **Field of Classification Search**

USPC D26/28-36; D12/187-190;
359/838-841

(57) **CLAIM**

The ornamental design for an extension arm with light and mirror for a road construction machine, as shown and described.

DESCRIPTION

FIG. 1 is a front side view of a second embodiment of the design for an extension arm with light and mirror for a road construction machine in the present application.

FIG. 2 is a left side view of the design for an extension arm with light and mirror for a road construction machine of FIG. 1.

FIG. 3 is a rear side view of the design for an extension arm with light and mirror for a road construction machine of FIG. 1.

FIG. 4 is a right side view of the design for an extension arm with light and mirror for a road construction machine of FIG. 1.

FIG. 5 is a top side view of the design for an extension arm with light and mirror for a road construction machine of FIG. 1.

FIG. 6 is a bottom side view of the design for an extension arm with light and mirror for a road construction machine of FIG. 1.

FIG. 7 is a perspective view onto the front side, left side and top side of the design for an extension arm with light and mirror for a road construction machine of FIG. 1; and,

FIG. 8 is a further perspective view onto the rear side and top side of the design for an extension arm with light and mirror for a road construction machine of FIG. 1.
